UNITED STATES PATENT OFFICE.

KURT RÜLKE, OF BERLIN, GERMANY.

PROCESS FOR THE MANUFACTURE OF DISINFECTANT SUBSTANCES AND PRODUCTS PRODUCED THEREBY.

1,020,624.

Specification of Letters Patent. Patented Mar. 19, 1912.

No Drawing.

Application filed December 7, 1911. Serial No. 664,377.

To all whom it may concern:

Be it known that I, KURT RÜLKE, chemist, citizen of Germany, subject of the King of Saxony and Emperor of Germany, residing at 18 Kielerstrasse, Berlin, in the Kingdom of Prussia and Empire of Germany, have invented new and useful Improvements in Processes for the Manufacture of Disinfectant Substances and Products Produced Thereby, of which the following is a specification.

This invention relates to processes for the manufacture of disinfectant fat-solvent substances and disinfectant soaps.

15 The process essentially consists in treating fenchone with solid or liquid soaps or their component materials.

By means of my invention I am able to manufacture solutions and emulsions of fenchone (an isomer of camphor), which in consequence of their solvent action upon most widely different substances are of great importance as a cleansing medium and moreover are characterized by possessing, in spite 25 of their non-poisonous nature, great disinfectant qualities. It is of special importance in this connection that it is possible to obtain in this way disinfectant soaps which possess a fenchone content of more than 10% 30 of the soap content.

Fennel-oil has previously been employed in soap making as a perfuming ingredient, but on the one hand fennel-oil does not in every instance contain fenchone; and this 35 employment of fennel-oil does not depend upon its fenchone content, as it is not fenchone but anethol that is responsible for the aromatic property of fennel-oil. Also the 40 quantity of fennel-oil added, and in a correspondingly higher degree the quantity of fenchone contained in this addition, is such a small proportion of the soap that only the perfuming effects would be caused by this addition. It has further been proposed to 45 manufacture disinfectant soaps by using camphor (an isomer of fenchone). Fenchone possesses much greater solubility than camphor and it is therefore possible by the use of fenchone to manufacture a much 50 more concentrated disinfectant soap than by the use of camphor, a fact which could not be foreseen. While camphor at the most dissolves to the extent of 10% in soap fenchone dissolves to the extent of over 70%. 55 It is obvious that the possibility of manufac-

turing soap with such a high disinfectant percentage offers very great advantages, as a definite percentage-content of disinfectant medium is necessary to obtain a disinfectant of practical account, since a too high soap 60 content would naturally entail a considerable increase in the cost of the disinfectant, and the disinfectant strength would suffer considerably owing to the disproportion between disinfectant medium and soap. Further, 65 the disinfecting strength of such high percentage fenchone soap is very much greater than that of camphor soap. The germ destroying strength of camphor soap is so slight, that practically it does not come 70 into account at all as a disinfecting medium. A solution of camphor in ricinolic sulfonate of soda in a diluted form which contains 1% of camphor, would not completely destroy 75 germs even after acting upon them for 7 hours. This effect is, in comparison with that of carbolic acid, so slight, that practically it is of no account. On the other hand a 40% fenchone soap in a diluted form with 1 part soap and 150 parts water kills, as experiments have shown, germs of *Bacterium coli commune* more rapidly than a 1% aqueous solution of carbolic acid. Even if there 80 has already been an intention of using fenchone as a substitute for camphor for technical purposes yet there could never have been an intention of using fenchone in this connection in the form of soap as a disinfecting medium, because camphor is of no account 85 for this purpose. 90

For the manufacture of fenchone soaps fenchone is mixed with resinous soaps, fat soaps or one of the otherwise known soaps or soap-mixtures. If the thus obtained solutions or emulsions of fenchone in soap are 95 mixed with water as a rule emulsions with good keeping qualities are formed, which may be used just as the solutions themselves. In consequence of their cleansing and disinfecting qualities these solutions and emulsions of fenchone are capable of application in very many different ways. For instance liquid soaps of fenchone dissolve dried oil colors and varnish easily and are consequently adapted for a cleaning medium for removing spots from clothes and similar purposes. The solutions and emulsions of fenchone are capable not only of being used as a disinfecting medium but may be employed also as an addition to 100 105 110

СОВЕТОВАЯ АССАДА СОВИКУ

baths for rheumatic persons, for the treatment of cutaneous eruptions and so on.

The solutions and emulsions of fenchone in soap may be solid, semi-solid or liquid according to the nature of the soap employed in each case. Also transparent soaps may be made with fenchone, eventually by the addition of alcohol. The manufacture of the soaps may take place either by mixing 10 the fenchone with the soap to be employed possibly under heat or also by mixing the component materials from which the soaps are manufactured with fenchone and then bringing about saponification according to 15 one of the usual methods.

Below a few examples are given to illustrate the manufacture of fenchone solutions.

Example 1: 1 part of fenchone is treated with 2 parts of medicinal potash soap. There results from this a cream like soap which dissolves in approximately 15 times as much water to a clear liquid.

Example 2: 1 part of phenone is mixed with 2 parts of semi-solid colophonium pitch, 25 ash soap, (prepared from 400 grams colophonium, 64 grams KOH and 130 grams water) and yields a soap liquid at ordinary temperatures.

Example 3: 600 grains benzene are treated with 270 grains colophonium, potash soap, and 180 grains solid C_8H_{16} (liquid soap), which is obtained by the saponification of cocoa-nut oil with the necessary quantity of 50% potash lye. (Here also a "liquid soap" results, which is not as good as the ordinary solid soap.)

Example 4: 67 parts of sulfonated castor oil are stirred in with 50 parts fetichone and the quantity of potash lye necessary for neutralization and water up to 150 parts.

In the manufacture of these foreshampoos and

58. In the manufacture of these fenchone so-
called from their flavor and the sweeping
sweat of aromatic gases to aromatic
spices, it is necessary to have a set of such
instruments as are commonly used in ap-
59. The sweeping with

solutions and emulsions the fenchone may be employed in the pure or impure state, as well as mixed with other materials. As fenchone dissolves other substances very easily its soap solutions and emulsions may incorporate many substances and so facilitate their application. For example in this way sulfur, formaldehyde, cresol, naphthol, thymol, chional, and the like as well as their derivatives may be incorporated in fenchone solutions or emulsions. If desired I may also add deodorizers and insoluble substances.

Having now described my invention what I claim and desire to secure by Letters Patent of the United States is

1. A process for the manufacture of disinfectant fat solvent substances consisting in treating fenchone with soaps. 60

2. A process for the manufacture of disinfectant fat-solvent substances consisting in treating fenchone with liquid soaps.

3. A process for the manufacture of disinfectant fat-solvent substances consisting in treating fenchone with the component materials of soaps.

4. A process for the manufacture of disinfectant fat-solvent substances consisting in treating teichoic with the component materials of liquid soaps.

5. Disinfectant fat-solvent soap having a free phenol content of more than 10% of the total soap content.

In testimony whereof I have hereunto set my hand in presence of two subscribing witnesses.

HENRY HASPER,
WOLDEMAR HAUPT.

и възможна една съществуваща във времето на съществуващия. Ако дадената съдържимателна същност е във времето на съществуващия, тогава тя е във времето на съществуващия. Ако дадената съдържимателна същност е във времето на съществуващия, тогава тя е във времето на съществуващия.
